US00D921954S

(12) **United States Design Patent** (10) **Patent No.:** **US D921,954 S**
(45) **Date of Patent:** **** Jun. 8, 2021**

(54) **LIGHT EMITTING DEVICE**

(71) Applicant: **Anker Innovations Technology Co., Ltd.**, Changsha (CN)

(72) Inventor: **Fangyuan Jiang**, Changsha (CN)

(73) Assignee: **Anker Innovations Technology Co., Ltd.**, Changsha (CN)

(**) Term: **15 Years**

(21) Appl. No.: **29/686,292**

(22) Filed: **Apr. 3, 2019**

(30) **Foreign Application Priority Data**

Oct. 11, 2018 (CN) 201830568128.7

(51) **LOC (13) Cl.** **26-03**

(52) **U.S. Cl.**
USPC **D26/72**

(58) **Field of Classification Search**

USPC D26/1, 24, 93, 104, 106, 72, 85
CPC F21V 21/14; F21V 3/00; F21S 6/00; F21S
6/002; F21W 2121/00; F21W 2131/00

(57) **CLAIM**

The ornamental design for a light emitting device, as shown and described.

DESCRIPTION

FIG. 1 is a front view of a light emitting device showing my new design;

FIG. 2 is a rear view thereof;

FIG. 3 is a left side view thereof;

FIG. 4 is a right side view thereof;

FIG. 5 is top view thereof;

FIG. 6 is a bottom view thereof;

FIG. 7 is a front top perspective view thereof; and,

FIG. 8 is a rear bottom perspective view thereof.

The broken lines depicting the remainder of the light emitting device form no part of the claimed design.

1 Claim, 8 Drawing Sheets

FIG. 1

FIG. 2

FIG. 3

FIG. 4

FIG. 5

FIG. 6

FIG. 7

FIG. 8
